COMBINED CIGARETTE SNUFFER AND ASH-
RECEIVING RECEPTACLE FOR PUBLIC TRASH
CANS

Edwin B. Feldman, Atlanta, Ga., assignor to Service En-
gineering Associates, Inc., Atlanta, Ga., a corporation
of Georgia

Filed Mar. 4, 1964, Ser. No. 78,863

Term of patent 14 years

(Cl. D85—2)

Fig. 2. Fig. 1. Fig. 3.

FIG. 1 is a perspective view of a combined cigarette snuffer and ash-receiving receptacle for public trash cans, embodying my new design;

FIG. 2 is a perspective view similar to FIG. 1 but showing only so much thereof as would appear above a trash can;

FIG. 3 is an exploded view;

FIG. 4 is a vertical sectional view;

FIG. 5 is a top plan view.

The broken line showings of a trash can in FIG. 2 and of a portion of a trash can in FIGS. 3 and 4 is for illustrative purposes only.

I claim:

The ornamental design for a combined cigarette snuffer and ash-receiving receptacle for public trash cans, as shown and described.
